1 Drawing Sheet

1

Genus and species: Calibrachoa sp.
Variety denomination: 'KLECA15327'.

BACKGROUND OF THE NEW PLANT

The present invention comprises a new and distinct variety of Calibrachoa, botanically known as Calibrachoa sp., and hereinafter referred to by the variety name 'KLECA15327'. 'KLECA15327' originated from a controlled cross conducted during summer 2012 in Stuttgart, Germany between the proprietary female Calibrachoa variety 'CA-2011-0540' (unpatented) and the proprietary male Calibrachoa variety 'CA-2012-0554' (unpatented).

In summer 2012 seed was collected from the controlled cross between the two Calibrachoa parental lines. The seeds were sown and plants were grown for evaluation in Stuttgart, Germany. A single plant was selected in May 2013 and was subsequently named 'KLECA15327'. In May 2013, 'KLECA15327' was first vegetatively propagated by tip cuttings. 'KLECA15327' was found to reproduce true to type in successive generations of asexual propagation via tip cuttings.

SUMMARY

The following are the most outstanding and distinguishing characteristics of this new variety when grown under normal horticultural practices in Stuttgart, Germany.

1. Yellow flowers; and
2. A vigorous habit.

DESCRIPTION OF THE PHOTOGRAPH

This new Calibrachoa plant is illustrated by the accompanying photograph which shows the whole plant, including the habit, the foliage, the flowers, and the buds. The photograph is of a four-month-old plant grown in a pot outdoors in Stuttgart, Germany in August 2014.

The colors shown are as true as can be reasonably obtained by conventional photographic procedures.

DESCRIPTION OF THE NEW VARIETY

The following detailed descriptions set forth the distinctive characteristics of 'KLECA15327'. The data which define these characteristics were collected from asexual reproductions carried out in Stuttgart, Germany. Data was collected on 12-week-old plants grown in a controlled glass greenhouse environment in Stuttgart, Germany in May 2015. Color references are to The R.H.S.
